UNITED STATES PATENT OFFICE.

JOHN ANDERSON, OF DULUTH, MINNESOTA.

AUTOMATIC DAMPER.

1,311,202.

Specification of Letters Patent. Patented July 29, 1919.

Application filed March 18, 1919. Serial No. 283,340.

To all whom it may concern:

Be it known that I, JOHN ANDERSON, a citizen of the United States, residing at Duluth, in the county of St. Louis and State of

5 Minnesota, have invented certain new and useful Improvements in Automatic Dampers, of which the following is a specification, reference being had therein to the accompanying drawing.

10 This invention relates to dampers for flues and has special reference to a novel form of such which is automatically regulated by the upward draft in the flue.

The principal object is to produce a practical and efficient device of this character.

Another object is that of providing simple and practical adjustable controlling means for the regulator.

20 Other objects and advantages will appear in the further description of the invention.

Referring to the accompanying drawings forming part of this application and in which like reference characters indicate like parts:

25 Figure 1 is a vertical central sectional view of the tubular housing containing the damper and which latter is shown in elevation in its inoperative position.

Fig. 2 is a similar view taken at right-angles to Fig. 1 and illustrating the damper in operative position, and

30 Fig. 3 is a side elevation of a fragmental portion of the damper housing, showing the damper regulator in elevation.

35 The embodiment of the invention here shown is designed especially for installation within a suitable enlargement of the flue in which it is placed. This enlargement, or drum, in the flue comprises two telescopic sections 1 and 2, the latter being made to fit snugly within the former.

The unions of the two portions 1 and 2, with their respective sections of the flue 3, are inclined, as at 4, forming a gradually tapered connection thereof.

45 The supporting frame of the damper-operating mechanism is rectangular in form and comprises the end walls 5 and 6 and the side walls 7 and 8, they being, if preferred, of one continuous strip of metal. However, I have found it convenient to construct said frame with the end walls 5 and 6 of considerably greater thickness than the side walls. This frame is made to fit snugly 50 within the smaller section 2 of the drum 1 and 2, its lowermost corners resting upon

the upper annular angle of the tapered connection between the section 2 and its respective portion of the flue 3.

When the device is thus placed within the 60 portion 2 of the drum, the portion 1 is slid down over it until the bevel 4 engages the upper corners of the frame, which results in a compact and pleasing external effect of the drum.

65 A shaft 9 is pivotally and centrally mounted intermediate of the two ends 5 and 6 of the frame upon two adjustable pivotal pins 10 and 11 securely fixed within the ends of the frame and whereby any wear in the 70 ends of the shaft may be compensated for and the mounting of the shaft neatly predetermined.

75 This shaft is screw-threaded from its lower end upwardly the major portion thereof and upon which is screw-threadedly mounted the hub 12, having a circular cap 13 thereupon, both of which are jammed and held in place by a suitable nut 14. Radially extending from two opposite sides of the 80 hub 12 are the two shafts 15, upon which are hingedly mounted the two semi-circular halves 16, which comprise the closing element or the damper proper. These halves have free pivotal action on the shafts 15 and 85 15 are actuated wholly by centrifugal force when carried about with the shaft 9.

80 Each half 16 has mounted thereupon, adjacent its lowermost peripheral edge, a suitable hemispherically shaped weight 17 and 90 by which the throw of the halves of the damper is governed.

95 A yoke or cross-head 18 is slidably mounted upon the shaft 9 above the nut 14 and pivotally carries, at 19, upon its radially extending opposed arms, depending rods 20, the lower ends of which are pivotally connected, as at 21, to the outer faces and approximately centrally of the halves 16 of the damper.

105 By this connection the two halves of the damper are obliged to operate uniformly and simultaneously and any movement of the damper will cause the cross-head 18 to reciprocate vertically upon the shaft 9, and it is apparent that any restriction of the upward movement of the cross-head 18 will limit the radial throw of the halves of the damper. To predetermine the extent of this action of the damper, I provide a horizontally disposed member 22, pivotally mounted at 23 in the depending bracket 24, fixed to

the upper end 5 of the supporting frame and having a forked or bifurcated end 25 straddling the shaft 9. The aperture 26 in the member 22, forming a coöperative part of 5 the pivotal connection of such member, is elongated longitudinally the member to permit of the necessary longitudinal reciprocation, due to the member being operated by the one-piece L-shaped rod 27, pivotally 10 mounted in the bracket 28, fixed to the upper end 5.

One end of the rod 27 is pivotally connected to the outer end of the member 22, as at 29, and the opposite end of the said 15 rod carries an enlarged sleeve 30 having a rectangular shaped hole 31 in the outer end thereof and into which hole may be thrust the flat-headed pin 32.

Upon the outer end of the flat-headed pin 20 32 is securely fixed, by a suitable rivet or pin 33, the balancing arm 34, having suitable notches therein in which the counter-weight 35 may be placed to determine the vertical limits of the cross-head 18.

25 When it is not desired to thus regulate the throw of the damper the counter-weight 35 may be hooked into a suitable hole in the short end of the balancing arm 34, as shown in Fig. 3, when the damper will be free to 30 operate to its normal limits.

Upon the shaft 9, adjacent its lower end is securely fixed by suitable jam nuts 36 and 37, or other convenient means, the propelling wheel 38, made of thin sheet metal and 35 having any suitable number of beveled buckets or blades to insure the proper rotating of the shaft 9.

From the above it is evident that any considerable upward draft of air in the flue 40 in which this device is installed, will cause the propeller wheel to rotate, thus rotating the shaft 9 and causing the halves 16 of the damper to operate, as above described.

When the halves of the damper are swung 45 outwardly, it is obvious that the draft of air up the flue will be checked and thus slow down the rotation of the propeller wheel, resulting in a limited uniform draft through the flue and which limitations may 50 be governed or set by the hand operated mechanism before described.

I am aware that somewhat similar devices of this nature have been patented and, therefore, do not claim broadly the idea of an automatically controlled damper, but the 55 novel patentable features of my present invention are deemed to be a decided advance in the art.

Having thus described my invention, what I claim as new and desire to secure by Letters Patent, is:

1. The combination with a flue damper of the character described, comprising a vertically disposed shaft, means for rotating said shaft and a centrifugally operated 65 damper, of a vertically reciprocable cross-head pivotally attached to the damper, horizontally disposed coöperating means extending to the exterior of the flue and manually adjustable therefrom: 70

2. The combination with a flue damper of the character described comprising a vertically disposed shaft, means for rotating said shaft and a centrifugally operated damper, of coöperating vertically reciprocable means 75 attached to the movable sections of the damper and means regulated from the exterior of the flue whereby the limit of the vertically reciprocable means may be predetermined. 80

3. In combination, a flue drum, a rectangular shaped frame slidably insertible within the drum, a rotatable shaft centrally mounted within the frame, a propeller wheel fixed to the shaft, a two-part hingedly suspended damper carried upon the shaft, means whereby the halves of the damper operate uniformly, horizontally disposed means for regulating the throw of the last mentioned means and extending to a point 85 adjacent the wall of one of the halves of the drum, and means within the drum whereby the latter may be set at a predetermined point of operation. 90

In testimony whereof I have hereunto affixed my signature in the presence of two witnesses.

JOHN ANDERSON.
